UNITED STATES PATENT OFFICE.

JOHN A. HOLMQUIST, OF WOODLAWN, PENNSYLVANIA.

WIRE-FENCE MACHINE.

1,378,955.

Specification of Letters Patent.

Patented May 24, 1921.

Application filed March 22, 1920. Serial No. 367,704.

To all whom it may concern:

Be it known that I, JOHN A. HOLMQUIST, residing at Woodlawn, in the county of Beaver and State of Pennsylvania, a citizen 5 of the United States, have invented or discovered certain new and useful Improvements in Wire-Fence Machines, of which improvements the following is a specification.

10 My invention relates to improvements in wire-fence machines, of the type known as the Denning machine and exemplified in the Denning Patents, Nos. 816,538 and 900,490. The characteristic of the Denning machine 15 is that in it both strand-wire feed and stay-wire feed are continuous, and the fence-forming instrumentalities act upon the wire under that fundamental condition.

In the operation of the Denning machine, 20 the ends of the stay wires are coiled about the strand wires while the strand wires are advancing in continuous progress through the machine; and, given the instrumentalities illustrated in the patents named, it is a 25 practical requisite that there be, during the coiling operation, no greater relative movement of the coiler longitudinally of the strand wire, than such as to allow for the gradual elongation of the coil as it is being 30 formed. Inasmuch as the rate of development of the coil longitudinally of the strand wire is relatively slow,—slower by far than a reasonable rate of strand-wire feed—the typical Denning machine is equipped with 35 flying coilers, coilers that advance and recede in the line of strand-wire advance and perform their essential coiling operation while advancing at equal speed with the strand wire—or, rather, to speak with minute ac- 40 curacy, at a speed slightly less than strand-wire speed, the margin of difference being due to the factor already mentioned: namely, the growth of the coil along the strand wire.

In the machine of the Bates type (see 45 Bates Patent No. 577,639), a machine 10 which the Denning stands contrasted in that strand-wire feed and stay-wire feed are in the Bates machine intermittent, there had been developed already, before Denning invented his continuous-feed machine, the idea 50 of imposing on the strand wires tension from a crimping drum rotating continuously and at uniform speed, but at the same time attaining intermittent movement of the 55 strand wires through the coilers, by interposing between the coilers and crimping

drum what is called a "take-up device," a device which intermittently develops and allows to diminish again a loop or bight in the advancing wire. The effect is that while 60 at one portion of their path of advance (around the crimping drum) the strand wires advance uninterruptedly and at constant speed, at another portion (through the coilers) they are part of the time at rest and 65 part of the time advancing at redoubled speed. This feature is fully described in Bates & Cocker Patent, No. 732,155 (Bates, 365,723).

I employ this take-up device, in order to 70 bring the strand wires intermittently to rest (or substantially so) in the coilers, and the first feature of my present invention has to do with improvements in the take-up device.

In the accompanying drawings, Figure I 75 shows in side elevation the fence machine of my present invention; Fig. II is a view in transverse vertical section, and to a larger scale, showing those instrumentalities wherein invention is found; and Fig. III is a plan 80 view of the table of the machine showing certain of the stay-handling instrumentalities.

The take-up device of the Bates & Cocker patent cited is in Fig. III of the drawings 85 illustrated *in situ* and in Fig. 5 is shown dissected out from the other machine parts. It consists essentially of three rollers (a^2 , a^1 , a^3) arranged in succession, longitudinally of strand-wire feed, the two end rollers 90 of the succession being stationary and being arranged on one side of the path of strand-wire advance and the intermediate roller of the succession being arranged on the opposite side of the path and being reciprocatory in a transverse direction, to alternately develop and release the loop or bight. This take-up device is incorporated in the machine of Letters Patent No. 1,082,697, granted on my application De- 95 cember 30, 1913. I now improve upon this take-up device, and, by rearrangement of the relative position of the parts, dispense with the two stationary rollers of the Bates & Cocker take-up, retaining only the reciprocating roller.

The machine as shown in side elevation in Fig. I includes, carried in a suitable frame, coilers 1, crimping drum 2, and a take-up device consisting essentially of a bight-forming roller 3. The dotted line a indicates the path of the strand-wires through the ma- 110

chine, and the arrow points upon this line indicate the direction of advance. The crimping drum 2 is, by suitable driving connections from the main driving shaft 4 of the machine, rotated, in direction (as shown in Fig. 1) the reverse of clockwise. It will be understood that there is a succession of strand wires advancing in parallel paths through the machine (in Fig. III 10 the succession of coilers 1 is shown, and through each it will be understood a strand wire is rising vertically); that they are drawn through the machine by means of the rotating crimping drum 2 which, gripping them, exerts tension upon them; and that the succession of parallel strand wires is united into an integrated fence by stay wires which at intervals span the spaces between adjacent strand wires, and which are applied as the strand wires pass through the coilers 1. In Fig. II the path of stay-wire feed is indicated by the arrow *b* and the dotted line along which the arrow is directed, and in Fig. III a succession of stay wires cut and ready for application to the strand wires is indicated by the letter *b'*.

Referring again to the Bates & Cocker patent (Fig. III), it will be observed that the strand wires advance in substantially direct line through the coilers and from the coilers to the crimping drum. Contrasted with this arrangement, the strand wires in my machine advancing from the coilers, are turned abruptly aside over roller 3, and pass thence to the crimping drum in a direction approximately at right angles to that in which they emerge from the coilers. Again, in the Bates & Cocker arrangement, the reciprocation of roller *a'* is in a direction transverse to the line of advance of the strand wires from the coilers; but in my machine the reciprocation of the roller 3 is in a direction parallel to the path of strand-wire advance from the coilers 1. In consequence, the strand wires advancing from the coilers meet roller 3 without deflection, and throughout all the range of reciprocation of roller 3 this straight-line advance of the strand wires is not disturbed. Delimiting rolls such as Bates & Cocker employ are dispensed with; one branch of the bight (that between the coilers and roller 3) lengthens and shortens but the wire there has no lateral swing; the other branch (that between roller 3 and crimping drum) lengthens and shortens, and incidentally the wire swings laterally. The points where the advancing strand wires meet the surface of the crimping drum are manifestly shifting points; but that, as will be understood, is not a matter to cause difficulty for the engineer, since this shifting occurs with determined periodicity.

Such motion as has been described is imparted to roller 3 by idly mounting it at

its opposite ends in pillow blocks 5 (Fig. II), and arranging these pillow blocks in slideways 6. There are two slideways, arranged one on either side of the machine; they are conveniently formed in or carried by the machine frame and are of course so positioned as to afford reciprocation of the roller in the relative direction already defined. The pillow blocks 5 are carried on pitmans 7, and these in turn are pivoted to crank arms 8 borne by a shaft 9, which shaft 9 is driven from the power shaft 4 already mentioned. It will be understood that shaft 9 extends across the machine from side to side, and that crank arms 8 and pitmans 7 are duplicated on either side of the machine.

Rotation of shaft 9 will by these instrumentalities effect rise and fall of the bight-forming roller 3, and the periodicity of this rise and fall is, as will be understood, correlated to the operation of the stay-forming instrumentalities.

The amplitude of the rise and fall of roller 3, and accordingly the degree of alternate acceleration and retardation of strand-wire feed through the coilers, may be varied by varying the effective length of crank arms 8.

The next feature of my invention concerns the reciprocation of the coilers. It is desirable that some degree of reciprocation be given them, particularly if they be (as preferably they are) coilers which are constantly rotating. The rhythmic succession of machine operations includes the cutting and positioning of the stay wires and then the engagement of the stay wires by the coilers, and it is desirable to have the coilers out of the way while the stay wires are being brought to position; then, when the stay wires are in position, the coilers advance, engage them, and coil their ends about the strand wires.

In the typical Denning machine, two motions were required of the coilers; one, that they rotate, and this rotation was a continuous one; and the other that they be "flying" coilers—that is to say, that they advance during the coiling operation at substantially uniform speed with the advancing strand wire, and then retract again. To meet these requirements, the Denning coilers were made telescopic; one portion having no motion longitudinally of the wires and serving to communicate rotation, the other portion being longitudinally reciprocal and imparting to the coilers the "flying" feature. Now, with the take-up device just described added to the machine, the rate of advance of the strand wires through the coilers at the time of coiling may be diminished to any desired degree, even to zero, and accordingly no other or further reciprocation of the coilers is re-

quired than such as will be sufficient to carry them out of the way in the intervals of their inaction, and when the stay wires are being brought to position.

5 A word more should be said about this movement of the strand wires during the coiling operation and its effect upon coiler reciprocation. As has been said, it is advantageous that the speed of strand-wire 10 advance be slightly greater than that of coiler advance (to allow for elongation of the coil as it is produced), and if strand-wire feed be diminished to that minimum, then of course the coilers will during 15 the coiling operation have no longitudinal motion, but only that of rotation. And with such an adjustment no other or wider range of coiler movement is required than is sufficient to afford the periodic clearance with 20 respect to stay-wire placement, already alluded to. But it is not a limitation upon me that the strand wires be so far retarded that the coilers are during the coiling operation longitudinally at rest; they may be 25 "flying" coilers still, and the range of flight may be great or small, as desired; and, of course, whatever range of flight may be required of them will be superposed upon the range of reciprocation to afford clearance 30 for stay-wire placement. Practically, I find it desirable to impose upon the coilers a fixed range of reciprocation, and then to adjust the throw of roller 3 accordingly. I find that, with the take-up device present 35 in the machine, a range of longitudinal movement of the coilers of five-eighths of an inch will suffice for all practical purposes.

Having so reduced the range of coiler 40 movement, it is no longer necessary to make the coiler in two parts telescopic, one relatively to the other, and the whole coiler may reciprocate as a unit, and still the essential rotary motion may continuously be imposed 45 upon it.

Referring particularly to Fig. II, the succession of coilers are mounted for rotation in a bar 10 which extends across the machine from side to side. This bar 10 is carried by 50 links 11 pivoted to it at either end upon levers 12, and to these levers is imparted a periodic swing such as to cause the desired longitudinal movement of the coilers, by means of eccentrics 13 upon shaft 9, upon 55 which the levers with their sustained parts rest by gravity.

Shaft 9, it will be noted, is conveniently the same shaft which through crank arms 8 imparts reciprocation to roller 3. It will 60 be seen that, with each turning of shaft 9, roller 3 makes one complete reciprocation and the battery of coilers 1 also makes one complete reciprocation; and it will be understood that, by suitable relative arrangement of crank arm 8 and eccentric 13 upon

shaft 9, proper correlation of the movements of these two parts may be effected.

In consequence of the relatively limited range of coiler reciprocation now required, I am able to impose upon the coilers, reciprocable though they are, continuous rotation from a power shaft rotating in stationary bearings. The bar 10 is provided at its ends with brackets or flanges 14, and to these flanges the links 11 may conveniently be pivoted. Between the opposite flanges 14 is journaled a shaft 15, and this shaft 15 may be rotated through sprocket connections 16' with an adjacent shaft, conveniently the main driving shaft 4 of the machine, which 75 is advantageously on the same level with it. The essential feature is that a sprocket drive from a fixed drive shaft will readily permit the driven shaft to range through a five-eighth-inch swing in a direction transverse 80 to a line connecting the centers of the two shafts.

A further feature of invention concerns the gearing through which the coilers are rotated. Reference to the Denning Patent, 90 No. 816538 (Fig. 10), will show the coilers driven by beveled gearing, and in actual construction the shaft (134) through which the coilers are driven extends across the path of direct feed of strand wires to coilers. 95 The Denning drawings, Fig. 3, Patent 816,538, show avoidance of this, but this method of avoidance has not been carried into practice. With the driving shaft extending across the axial line of the coilers, it 100 is necessary that the strand-wires in their approach to the coilers shall follow a path which departs from the axial line, and, in the Denning machine as it has hitherto been built and used, the strand-wires in approach 105 to the coilers rub upon the surface of this gear shaft. Through continued use the shaft so rubbed upon is worn away; the effect on the wire too is bad, for deflection under tension and the progressively advancing bend over a rigid surface tends to break and loosen the galvanized coating.

I eliminate this difficulty. I dispense with the beveled-gear drive of the Denning patent, and employ instead a worm-gear 115 drive. In consequence, it becomes possible to arrange the driving shaft 15 of the gearing (the shaft driven from shaft 4 by sprocket chains, as already explained) to one side of the axial line of the coilers. The 120 shaft 15 is provided with a worm and each coiler is provided with a worm-engaging pinion 16. The wires, as clearly shown in Fig. II, approach the coilers in axial line, and the tension upon the strand wires is direct, from roller 3 to sheaves 17 (see Fig. I).

The particular features of structure in which my invention resides, it will be understood, are not necessarily limited in applicability to machines of the Denning type, 130

much less to the specific structure with which they are here in exemplary manner associated; furthermore, as will be understood, the invention may still be practised, though 5 instrumentalities be modified. In the ensuing claims I define the essential features of my invention. So long as those features be present, the form of the presentation is irrelevant.

10 I claim as my invention:

1. In a wire-fence machine, the combination of a plurality of parallel coilers, a take-up roller arranged transversely of said coilers and beyond the delivery ends thereof, 15 and reciprocable in the direction of the longitudinal extent of said coilers, and means for drawing strand wires through said coilers and over said roller, substantially as described.

20 2. In a wire-fence machine, the combination of a plurality of parallel coilers, a take-up roller arranged transversely of said coilers and beyond the delivery ends thereof and tangent to the prolonged axes of said 25 coilers, and reciprocable in the direction of the longitudinal extent of said coilers, and means for drawing strand wires through said coilers and over said roller, substantially as described.

30 3. In a wire-fence machine, the combination of a plurality of longitudinally reciprocable parallel coilers, a take-up roller arranged transversely of said coilers and beyond the delivery ends thereof and reciprocable in the direction of the longitudinal 35 extent of said coilers, means for reciprocating said coilers and said roller in correlation each to the other, and means for drawing strand wires through said coilers and over 40 said roller, substantially as described.

4. In a wire-fence machine, the combination of a plurality of longitudinally reciprocable parallel coilers, a take-up roller arranged transversely of said coilers and beyond the delivery ends thereof and reciprocable in the direction of the longitudinal extent of said coilers, means for drawing strand wires through said coilers and over said roller, substantially as described.

5. In a wire-fence machine, the combination of a reciprocable bar, a succession of 50 coilers rotatably mounted in said bar with axes transverse to the length of said bar and parallel one to another, a shaft rotatably mounted in said bar, means for reciprocating said bar, means for imparting continuous rotation to said shaft while said bar reciprocates, and means for imparting rotation from said shaft to said coilers, substantially as described.

55 6. In a wire-fence machine, the combination of a reciprocable bar, a succession of coilers rotatably mounted in said bar with axes transverse to the length of said bar and parallel one to another, a shaft rotatably mounted in said bar, means for reciprocating said bar, means for imparting continuous rotation to said shaft while said bar reciprocates, and means for imparting rotation from said shaft to said coilers, substantially as described.

60 7. In a wire-fence machine, the combination of a reciprocable bar, a succession of coilers rotatably mounted in said bar with axes transverse to the length of said bar and parallel one to another, a shaft rotatably mounted in said bar, means for reciprocating said bar, means for imparting continuous rotation to said shaft while said bar reciprocates, and worm gear connection between said shaft and said coilers, substantially as described.

75 8. In a wire-fence machine, the combination of a reciprocable head bearing a rotatable coiler, a rotating shaft adjacent which said reciprocable head is arranged, and coiler-rotating means including a sprocket drive extending from said shaft to said head and in a direction transverse to the line of reciprocation of said head, substantially as described.

In testimony whereof I have hereunto set my hand.

JOHN A. HOLMQUIST.
